UNITED STATES PATENT OFFICE.

PAUL A. KOPP AND JOHN P. KOPP, OF TULSA, OKLAHOMA.

CLASP.

1,385,009.

Specification of Letters Patent. Patented July 19, 1921.

Application filed June 30, 1919. Serial No. 307,592.

To all whom it may concern:

Be it known that we, PAUL A. KOPP and JOHN P. KOPP, citizens of the United States, residing at Tulsa, in the county of Tulsa, State of Oklahoma, have invented certain new and useful Improvements in Clasps; and we do hereby declare the following to be a full, clear, and exact description of the invention, such as will enable others skilled in the art to which it appertains to make and use the same.

This invention relates to an improvement in clasps and more particularly to a spring clasp adapted for use in connection with articles to be held in one's pocket so as to securely engage the cloth of the pocket in order to securely hold the device to which it is attached, in position.

The invention further comprehends an improved clasp adapted for use particularly in connection with an eyeglass or spectacle case adapted to be fastened to the cover of the case and including improved means for securing the device in position and a simple and novel construction of clasp and spring arrangement whereby a double gripping action is obtained.

With the above objects and others in view, as will appear as the specification proceeds, the invention comprises certain novel and useful combinations and arrangements of parts as will hereinafter be more particularly pointed out and claimed.

Reference is had to the accompanying drawings forming a part of this application wherein like reference characters represent corresponding parts throughout the several views and wherein:

Figure 1 is a plan view of a case provided with our improved clasp.

Fig. 2 is a sectional view of the case with the clasp applied thereto, and

Fig. 3 is a transverse sectional view.

Referring to the drawings in detail, the numeral 10 designates an eyeglass or spectacle case having the usual hinged cover 11 normally held in a closed position in the usual manner by means of a spring, as is common in the art. The clasp includes a strip 12 having a reduced portion 13 terminating in a ball terminal or enlargement 14 formed in any desirable manner to engage the outside of the cloth of the pocket so as to form an efficient grip without tearing the cloth.

The opposite end of the strip is of suitable

fanciful design and enlarged as shown at 15 to form a grasping portion, said portion being slightly off set forwardly as is clearly indicated in Fig. 2 of the drawings. The strip 60 is also provided with oppositely extending portions 16 forming a bridge piece which is substantially in the form of a cross arm. These extensions are pivoted in two pedestals or pivot members 17 which are secured 65 through the cover of the case 10 and headed as shown at 18, in Fig. 2 of the drawings.

In connection with the strip 12 of the clasp, there is employed a U-shaped spring wire 19 which has a forwardly off set bight 70 portion 20 fitting over the reduced portion 13 of the strip 12 adjacent to the enlargement 14, the leg portions of the spring extending along either side of the strip and parallel to each other and the strip and having their extremities coiled about the extensions 16 from the outer to the inner ends of said extensions for contact with the opposed edges of the strip of the clasp. These coils are wound in the same direction and 80 the free extremities of said leg portions are extended to contact with the cover 11 as shown at 21 thereby causing the coils or springs to exert tension through the medium of the U-shaped arm thus provided in connection with the sides or leg portions and the bight portion 20, against the lower end of the clasp strip whereby to bring the enlargement into frictional engagement to grip the cloth between it and the cover of the 90 case. It will be further noted that the leg portions of the spring wire lie between the strip 12 and the cover 11 of the case and in close spaced relation to the cover. Thus, when the case is placed within the pocket 95 of the wearer with the cloth constituting the outer side wall of the pocket, between the lid of the case and the ball head 14, further downward movement of the case will carry the cloth beyond the head 14 and into position between the legs of the wire 19 and the case cover 11. Thus, these legs will clasp the cloth against the cover in addition to the clasping action of the head 14 while they will permit the face of the ball 14 to 105 sink into the cloth to a greater degree than do the legs in consequence of its lesser bearing surface. The cloth constituting the outer wall of the pocket is thus clasped by both the ball head 14 and the legs of the 110 wire 19, the legs of the wire determining the extent to which the ball head 14 may be

pressed into the cloth so that such pressure may not be excessive. It is to be understood that the case is received within the pocket and thereby securely held in position, although it is obvious that the same construction of clasp may be employed with other articles to be held in the pocket, as will be obvious.

From the foregoing, it will be seen that we have provided a very simple and efficient form of clasp which while particularly designed for use in connection with an eye-glass or spectacle case, will be well adapted for other articles wherein the same form of mounting may be employed as hereinbefore described. The device can be very cheaply produced in a practical way and will obviate the possibility of the case dropping out of the pocket and thereby resulting in the breaking of the glasses contained therein.

What is claimed is:

1. The combination with an article to be held, of a clasp strip pivoted thereto in spaced relation to it and having a clasping terminal portion disposed to lie normally against said article and a spring wire associated with the clasp strip for holding the clasping terminal in coöperative clasping relation to the article, the spring wire between

the clasping terminal of the strip and the 30 pivot of the strip being in close spaced relation to the article for clasping action thereagainst supplemental to the terminal of the clasping strip.

2. The combination with an article to be 35 held and having spaced posts and a clasping strip pivoted between them in spaced relation to the article except at its terminal which is adapted to contact normally with the article, of a spring wire bearing at its 40 ends against the article at the opposite side of the pivot of the strip from its contacting terminal and having its intermediate portion exposed across the outer side of the strip adjacent its said terminal with the portions of the wire between the terminal and the pivot of the strip in close spaced relation to the article and between the article and the strip, whereby to exert a clasping action in connection with the article and 45 supplemental to the said terminal.

In testimony whereof we affix our signatures in the presence of two witnesses.

PAUL A. KOPP.
JOHN P. KOPP.
